CARBONATOR

James L. Hudson, Detroit, Mich.

Application September 16, 1946, Serial No. 697,364

8 Claims. (Cl. 261—21)

1

This invention relates to carbonators, especially carbonators intended for use in automatic cup vending machines which are usually so located that it is not convenient or desirable to connect them with a water main and, consequently, they have to be provided with a tank of water and a pump for pumping the water into the carbonating tanks against the pressure obtaining in these tanks.

The apparatus is arranged to automatically start the pump when the water in the tank or tanks falls below a given level and to automatically stop the pump when the water reaches a given level. This is done by the aid of a column of pans which rises and falls with the water in the tank. These pans serve not only the function of a controlling float, but they also serve to aid in the mixture of the gas and the water. The rise and fall of these pans serves to open and close a valve in a water line which in turn controls the pump by a pressure switch, as will be more fully described hereinafter.

Another important feature of the invention is the use of capillary tubes or other means of restriction in the lines used for connecting the several tanks above the water level for the purpose of equalizing the pressure in the tanks and maintaining the same water level in all the tanks by allowing a slow feed of gas from tank to tank, thus preventing "pocketing" or trapping more gas in one cylinder than the others. This arrangement also permits the weight of the column of water in the control tank to force the gas into the top of the second and third cylinders back through the restrictor lines into the top of the control cylinder where it is mixed with the incoming water and is absorbed, thus permitting all the tanks to refill without appreciably raising the pressure in the carbonator, which must be held constant in order to match the feed of syrup to the mixing faucet.

The member which controls the water valve can also be used at the same time to control the gas valve in the controlling tank.

In the drawings:

Fig. 1 is a side elevation partly in section showing the carbonating apparatus.

Fig. 2 is a plan view.

Fig. 3 is an enlarged longitudinal section of the controlling tank.

Fig. 4 is a detail of the water valve.

Fig. 5 is a section on the line 5—5 of Fig. 4.

Fig. 6 shows a modified form of restricted connection between two tanks.

P is a pump driven by a motor M. The pump is

connected with any source of water, such as a tank, or it may be the city water. This pump pumps the water through the cooling coil 4 which may be cooled by ice or artificial refrigeration (not shown). The pipe 2 connects the cooling coil with the controlling or primary tank 3. A needle valve 43 controls the entry of the water into the tank 3. One or more auxiliary tanks 5 are connected with the primary tank and each other by means of the pipes 6 at the bottom of the tanks. These pipes allow the water to run freely from the primary tank to the auxiliary tanks. 7 is an outlet pipe to the dispensing spigot or mixing faucet 70. 8 is a gas tank for containing carbon dioxide or other gas under pressure. This tank is provided with a pressure-reducing valve 9. Pipe 10 connects the pressure-reducing valve with the check valve 11. Pipe 12 leads to the primary tank 3, the tube 13 passing to the bottom of the tank where the discharge opening is controlled by a needle valve 14. However, this discharge valve may be omitted, but it is desirable. The pipe 15 leads from the top of the control tank to the auxiliary tanks where the gas passes through pipes 16 which lead from the tops of the tanks to the bottoms where gas is free to discharge into the water.

The primary tank has a stack of pans 17 that are fastened to the rod 18. These pans are filled with water as the highest one is below the water level when the tank is filled to its maximum level. When the water level in the several tanks falls below a given level, these pans are exposed below the water level at the top and the weight of the pans filled with liquid overcomes the buoyancy of the liquid and the pans drop. The rod 18 is connected at 19 with a lever 20 which is in the form of a yoke (see Fig. 5) with two arms pivoted to the posts 21. A lever member 22 in the form of a channel is pivoted on pin 23 which is fastened to the arms 24 of a block 25 which is secured to the head plate or cap 26 of the tank. This block 25 has a sleeve 27 projecting through the top of the cap. The sleeve is internally threaded and is adapted to receive a pipe union 28 which has incorporated in one end a valve opening 29 and the valve guide 30. The needle valve 43 is guided up and down by this guide 30. A block 31 is secured to the channel-like lever 22 by the screw 32. This block carries the wire arms 33 which engage an annular groove 34 (Fig. 3) so as to connect the needle valve with the actuating lever 22. The swinging end of the lever is connected by pin 35 with the draft link 36 which connects with the lower lever 37 that is

pivoted at 38 to bracket 39. This lever controls the needle valve 14 that in turn controls the gas outlet 41. Referring to Fig. 5 it will be seen that the ends of pin 35 are connected by springs 42 with the lever yoke 20. These levers and springs are an assembly which forms a snap-over-center actuator. Hence, when the stack of pans reaches a given point in its rise or descent they actuate the lever yoke 20 and when that reaches the midpoint of its movement the springs snap over center and give a snap action to the valve in opening or closing.

The stack of accumulator pans controls the motor switch S indirectly and not by a direct lever or link connection which would have to pass through the tank and be a source of trouble due to gas leakage. The control is indirectly by controlling the upper needle valve 43. When the pans or buoy descend and the controlling lever 22 snaps over center and opens the valve, this allows the water in the coil and pipe leading from the pump to enter the primary tank. This water in the coil is sealed in the coil under pressure when the valve 43 is closed. The air cushion coil 44 traps air which permits the sealing of a given pressure in the water coil and pipe. It also prevents "hammer" noises when the valve shuts off or when water is running, and prevents the motor "short-cycling" if there is a small leak in the valve seat. The diaphragm pressure switch S may be set to cut off the motor when the pressure in the water coil reaches 130 pounds. The reducing valve 9 in the gas tank may be set to keep the gas pressure at 90 pounds. Hence, the pressure in the tanks will always be 90 pounds. When the buoy drops and the water valve 43 opens, the 130-pound pressure in the water coil is immediately reduced. The diaphragm switch may be set so that when the pressure drops to 110 pounds it closes the motor switch and starts the motor and starts the pump pumping water into the primary tank and through the pipes 6 to the auxiliary tanks. When the liquid level rises high enough to raise the buoy to the point where it again throws the snap actuator over center, this closes the valve 43. The pump continues until the pressure in the coil builds up to 130 pounds, thereupon the switch S will automatically open the motor circuit and stop the pump. Hence, the motor and the pump are controlled by the buoy, the valve, the pressure in the water pipe line and the pressure switch. This control eliminates any operating connections passing out of the tank which might cause leakage of gas. It also prevents short circuiting of the electrical connections of the so-called "electrode" water level controls.

The gas in each tank is discharged at the bottom of the tank so that it may percolate upwardly through the water and be absorbed. The pans have the function of forming baffles to prevent the too easy rise of the gas in the water so as to tend to prevent the gas from passing through the water without becoming absorbed. The turned-over lips of the cups or pans trap gas and facilitate the absorption of the gas into the water. This is explained and claimed in my Patent No. 2,441,419, of May 11, 1948. The pans 45 in the auxiliary tanks are fastened directly to the gas tubes 16 and are stationary. They do not move upwardly like the pans 17 of the primary tank. Baffle plate 46 is secured in the bottom of the first tank to impede the upward movement of the gas to cause better absorption of the gas in the water.

It is desirable that the pressure in the tanks be equalized and, consequently, suitable connections are provided at the top of the tanks for this purpose but to prevent too rapid equalization of this pressure restrictive tubes 47 are used. A capillary tube forms a considerable resistance to flow of gas, due to the friction provided by the tube, and also the turbulence of the gas where such a small tube is used. These capillary tubes are preferably about .062 or $1\frac{1}{8}$ of an inch in their I. D. It is undesirable to have an unimpeded communication from one tank to the other because if the pressure builds up in one tank faster than in another then some of the free gas at the top of the one tank will pass to the tank of lower pressure without passing through the water in that tank. I can use a restricted orifice in place of a capillary tube, and such a connection between the two tanks is shown in Fig. 6. It is the desideratum to have a maximum amount of the gas pass through the water and this is achieved by having the gas inlets all at the bottom of the several tanks and having pressure-equalizing passages resistant to the flow of the gas from one tank to the other.

The accumulator pans or cups 17 (the buoy) are held up when empty by means of the springs 48. These springs cooperate with the buoyancy of the water to tend to hold the buoy in the upward position. As already explained, when the water level drops there is sufficient decrease in the buoying force so that the water in the pans overcomes the buoyance of the water and the pull of the springs 48. When the tanks are first installed and there is no water in them, the springs 48 cause the valve to be closed. If the pump were turned on the water could not flow into the tank, hence some means must be provided to manually open the valve against the pull of the springs 48. This is provided in a plunger 49 which has a spring 50 that ordinarily presses it upwardly. One can push down on this plunger and thereby open the valve to allow the tank to fill with water. Once the tank is filled this plunger may never have to be used again. In order to prevent leakage around this plunger, which is the only moving part passing through the tank, a packing and a jamb nut can be provided so as to seal the opening. These can be tightened down after the plunger has been used once to start the apparatus. This jamb nut is not shown as it is no part of the invention.

As stated above, the lower needle valve 14 is not essential, but I find it desirable because by closing off the supply of gas while the water is coming in this reduces a rise in pressure in the tank due to the pressure generated by the pump and also from gas being admitted from the pressure reducing valve in the gas storage tank.

The air cushion connected with the water line performs a useful function in preventing the too frequent operation of the pump as well as protecting the pump in stopping it. If the pump operated against an unyielding wall of liquid when the pressure reached the point for the motor switch to open, the pump and motor would be stopped too suddenly. The air pad eases the stoppage. Furthermore, it prevents the too frequent cycling of the motor and pump for if there were an unyielding wall of water between the pump and the valve without an air cushion, every time a few drops of water leaked out the valve the pressure would be reduced and the apparatus would start to cycle.

I claim:

1. A carbonator having in combination, a control tank with a fresh water inlet, a valve therefor with a liquid level control therefor, means including a reducing valve for supplying gas under a definite pressure to the bottom of the control tank, means for supplying water under pressure to said control tank always at a pressure greater than said definite gas pressure, one or more auxiliary tanks, water connections at the bottom of all the tanks for connecting the control tank with the auxiliary tanks in series, means for supplying gas under said definite pressure to the bottom of the auxiliary tank or tanks, a draft connection with the lower end of the auxiliary last tank in the series whereby carbonated liquid is drawn only after it has passed through all the tanks, pipe connections between the top of the tanks having restrictions therein to permit the gradual equalization of the gas volume in the several tanks but preventing the free flow of gas from one tank to the other.

2. A carbonator having in combination, a control tank with a fresh water inlet, a valve therefor with a liquid level control therefor, means including a reducing valve for supplying gas under a definite pressure to the bottom of the control tank, means for supplying water under pressure to said control tank always at a pressure greater than said definite gas pressure, one or more auxiliary tanks, water connections at the bottom of all the tanks for connecting the control tank with the auxiliary tanks in series, gas supply connections from the top of the control tank to the bottom of the auxiliary tank or tanks, a draft connection with the lower end of the auxiliary last tank in the series whereby carbonated liquid is drawn only after it has passed through all the tanks, pipe connections between the top of the tanks having restrictions therein to permit the gradual equalization of the gas volume in the several tanks but preventing the free flow of gas from one tank to the other except through the gas flow conduits that discharge at the bottom of the auxiliary tank or tanks.

3. The combination claimed in claim 1 in which the pipe connections for equalizing the volume of gas in each tank are capillary tubes.

4. The combination claimed in claim 1 in which the means for supplying water under pressure to the control tank is a motor operated pump in which an automatic switch starts the motor when the liquid level control opens the water valve and cuts the motor off when the said control closes the valve.

5. The combination claimed in claim 1 in which the means for supplying water under pressure to the control tank is a motor operated pump in which an automatic switch starts the motor when the liquid level control opens the water valve and cuts the motor off when the said control closes the valve, the said switch being set to start and cut off the motor at pressures higher than the said definite gas pressure.

6. A carbonator for use in combination with a source of charging gas under pressure and a source of water, having in combination a charging tank, a pressure reducing valve and pipe between the source of charging gas and the tank for definitely fixing the maximum pressure of the gas in the tank, a water line leading from the water source to the charging tank, a pump in the water line, an electric circuit and motor for driving the pump, an air trap leading off the water line on the delivery side of the pump and receiving pressure only from the water from the pump, a water pressure controlled switch connected to the water line and independent of said air trap for opening and closing the motor circuit, a valve in the tank controlling the water issuing from the water line into the tank, a float member rising and falling with the water level in the tank for controlling said valve having connections when the water level in the tank falls below a given level to open the valve thereby reducing the pressure in the water line and in the air trap, thereby also decreasing the pressure on the water pressure controlled switch to close the switch and to start the pump pumping more water into the tank and raising the water level, said connections when the water level rises above a given level automatically closing the valve while the pump continues to operate to raise the pressure in the water line and the air trap to a definite point at which the water pressure-operated switch is automatically thrown open to break the motor circuit and stop the motor and

10 line on the delivery side of the pump and receiving pressure only from the water from the pump, a water pressure controlled switch connected to the water line and independent of said air trap for opening and closing the motor circuit, a valve in the tank controlling the water issuing from the water line into the tank, a float member rising and falling with the water level in the tank for controlling said valve having connections when the water level in the tank falls below a given level to open the valve thereby reducing the pressure in the water line and in the air trap, thereby also decreasing the pressure on the water pressure controlled switch to close the switch and to start the pump pumping more water into the tank and raising the water level, said connections when the water level rises above a given level automatically closing the valve while the pump continues to operate to raise the pressure in the water line and the air trap to a definite point at which the water pressure-operated switch is automatically thrown open to break the motor circuit and stop the motor and the pump, the said switch operating in cutting off and switching on the current at and in a pressure range greater than the maximum gas pressure controlled by the pressure reducing valve, the said float and said connections comprising a plurality of spaced pans supported on a rod which connects with levers and springs which in turn connect with the valve, the said levers and springs arranged in a snap-over-center assembly, one or more auxiliary tanks which are connected at the bottom with the charging tank for passage of water from one tank to another and which have pipe connections to deliver the gas under pressure below the water level in said tanks, and means for connecting the auxiliary tanks above the liquid level to equalize the pressure, but said connections retarding the flow and equalization of the gas pressures.

15 7. A carbonator for use in combination with a source of charging gas under pressure and a source of water, having in combination a charging tank, a pressure reducing valve and pipe between the source of charging gas and the tank for definitely fixing the maximum pressure of the gas in the tank, a water line leading from the water source to the charging tank, a pump in the water line, an electric circuit and motor for driving the pump, an air trap leading off the water line on the delivery side of the pump and receiving pressure only from the water from the pump, a water pressure controlled switch connected to the water line and independent of said air trap for opening and closing the motor circuit, a valve in the tank controlling the water issuing from the water line into the tank, a float member rising and falling with the water level in the tank for controlling said valve having connections when the water level in the tank falls below a given level to open the valve thereby reducing the pressure in the water line and in the air trap, thereby also decreasing the pressure on the water pressure controlled switch to close the switch and to start the pump pumping more water into the tank and raising the water level, said connections when the water level rises above a given level automatically closing the valve while the pump continues to operate to raise the pressure in the water line and the air trap to a definite point at which the water pressure-operated switch is automatically thrown open to break the motor circuit and stop the motor and

the pump, the said switch operating in cutting off and switching on the current at and in a pressure range greater than the maximum gas pressure controlled by the pressure reducing valve, the said float and the said connections comprising a plurality of spaced pans supported on a rod which connects with levers and springs which in turn connect with the valve, the said levers and springs arranged in a snap-over-center assembly, one or more auxiliary tanks which are connected at the bottom with the charging tank for passage of the water from one tank to another and which have pipe connections to deliver the gas under pressure below the water level in said tanks, and means for connecting the auxiliary tanks above the liquid level to equalize the pressure, but said connections retarding the flow and equalization of the gas pressures, the said means comprising one or more capillary tubes.

8. A carbonator for use in combination with a source of charging gas under pressure and a source of water, having in combination a charging tank, a pressure reducing valve and pipe between the source of charging gas and the tank for definitely fixing the maximum pressure of the gas in the tank, a water line leading from the water source to the charging tank, a pump in the water line, an electric circuit and motor for driving the pump, an air trap leading off the water line on the delivery side of the pump and receiving pressure only from the water from the pump, a water pressure controlled switch connected to the water line and independent of said air trap for opening and closing the motor circuit, a valve in the tank controlling the water issuing from the water line into the tank, a float member rising and falling with the water level in the tank for controlling said valve having connections when the water level in the tank falls below a given level to open the valve thereby reducing the pressure in the water line and in the air trap, thereby also decreasing the pressure on the water pressure controlled switch to close the switch and to start the pump pumping more water into

the tank and raising the water level, said connections when the water level rises above a given level automatically closing the valve while the pump continues to operate to raise the pressure in the water line and the air trap to a definite point at which the water pressure-operated switch is automatically thrown open to break the motor circuit and stop the motor and the pump, the said switch operating in cutting off and switching on the current at and in a pressure range greater than the maximum gas pressure controlled by the pressure reducing valve, the said float and the said connections comprising a plurality of spaced pans supported on a rod which connects with levers and springs which in turn connect with the valve, the said levers and springs arranged in a snap-over-center assembly, one or more auxiliary tanks which are connected at the bottom with the charging tank for passage of the water from one tank to another and which have pipe connections to deliver the gas under pressure below the water level in said tanks, and means for connecting the auxiliary tanks above the liquid level to equalize the pressure, but said connections retarding the flow and equalization of the gas pressures, the said means including a restricted orifice.
